INVENTOR.

SAMUEL M. KITCHEN

BY *Harry D. Wallace*
ATTORNEY.

UNITED STATES PATENT OFFICE.

SAMUEL M. KITCHEN, OF SKANEATELES, NEW YORK.

SCYTHE.

1,187,432.

Specification of Letters Patent. Patented June 13, 1916.

Application filed August 25, 1915. Serial No. 47,374.

To all whom it may concern:

Be it known that I, SAMUEL M. KITCHEN, a citizen of the Kingdom of Great Britain, residing at Skaneateles, in the county of 5 Onondaga and State of New York, have invented certain new and useful Improvements in Scythes, of which the following is a specification.

This invention relates to improvements in 10 scythes, and the invention relates particularly to the construction of the scythe blade, in combination with a tang and supporting plate to which the blade is attached.

The object of the invention is to simplify 15 and improve the construction of the blade to the extent of rendering the same strong and durable, and at the same time produce a lighter blade than heretofore, the particular aim of the invention being to cheapen the 20 cost, by materially lessening the amount of labor and material.

A further object is to provide a form of 25 blade whereby a better or higher grade of steel may be employed than when the blade and tang are made in one part. And a further object is to provide a scythe blade which is particularly adapted for cutting or 30 mowing lawns, wherein the grass is invariably cut shorter than is the case in ordinary field or farm work.

The invention further relates to an improvement of the devices shown and described in United States Patent No. 992,476, to Bartlett, bearing date May 16, 1911.

35 The various features and parts of the invention will be understood from the detailed description which follows, and by reference to the accompanying drawing, in which—

40 Figure 1 is a plan or top side view of the blade, to which is connected one form of my improved tang and supporting plate. Fig. 2 is a broken bottom side view of the same; showing the manner of inter-locking the 45 blade and the supporting plate. Fig. 3 is an enlarged detail sectional view, taken on line 3—3 of Fig. 1. Fig. 4 is a cross-section, taken on line 4—4 of Fig. 1. Fig. 5 is an under-side view of the tang and supporting 50 plate; showing the curved socket or recess which receives the heel of the blade. Fig. 6 is an end view of the same. Fig. 7 is a cross-section taken on line 7—7 of Fig. 2. Fig. 8 is a view of a modified form of the 55 tang. Fig. 9 is a broken plan view of the

blade; showing the construction of the heel-end.

In the drawing, 2 represents my improved blade, which is preferably made out of sheet steel, and which is capable of taking 60 a high temper for producing a keen cutting edge 3. The opposite or rear edge of the blade 2 is provided with an upturned flange 4, which is preferably arranged substantially at right angles to the plane of the 65 blade. Both the blades and the flange 4, are preferably plain and smooth, so as not in any way to obstruct or interfere with the free and effective working of the said parts. By this construction and arrangement of the 70 blade, its underside is preferably smooth and flat, and as the bevel of the cutting edge 3 is disposed on the top side of the blade, the user of the scythe is able to cut the grass or weeds closer to the ground, than is possible 75 under the construction shown in the patent referred to, as well as in many of the older styles of scythe blades. By eliminating the V-shaped groove or channel, and the corresponding bead, adjacent the rear 80 flange, as shown in the Bartlett patent referred to, I am able to produce a blade which is considerably lighter and yet sufficiently strong to do its work and the expense of constructing my improved blade 85 is comparatively small. The heel-end of my blade 2, is preferably rounded off at 5, and this part extends beyond the heel-end of the flange 4. The blade 2 is strongly supported by a plate 6, which over-lies the top side or 90 face of the blade, and the said plate is cut away at its rear side to form a curved socket or recess 7, having a substantially L-shaped shoulder 7' to receive and support the correspondingly shaped heel-portion 5 of the 95 blade. The plate 6 is also provided at its rear-edge with an upturned flange 8, which extends substantially the length of the socket 7, and the said flange alines with and abuts the heel-end of the flange 4 of the 100 blade. By this peculiar construction of the plate 6, the blade and plate are interlocked, and when these parts are suitably secured together by a plurality of rivets 9, the whole construction possesses extreme strength, and the blade and plate are not liable to work loose, or the interlocked joint to yield or give away. By providing the flange 8, the plate 6 may be made of a lighter gage of 105 metal and still afford adequate strength for 110

supporting the relatively long and heavy blade.

The free end of the plate 6 is formed with a tang 10 which is arranged to connect in the usual manner with a suitable snath. The tang shown in Figs. 1, 2, 5 and 6, is what is known as the European tang, while the tang shown in the modified view, Fig. 8, is the common American tang. Both forms of the tangs are now in common use in this country, and both are equally applicable to my blade and plate, although they require slightly differently constructed snaths. The important features of my supporting plate 6 is that by the peculiar and novel construction of the socket or recess 7 and the flange 8, it adds great strength to and adequately supports the heel-end of the blade, which is subjected to the greater part of the strain during the mowing operations, and the said plate may also be made lighter and smaller in area than heretofore.

All of the foregoing novel features, and advantages enable me to produce a scythe blade which is strong and durable, light in weight, a keen cutter, and the cost of construction is materially reduced.

What I claim is—

1. In a scythe, the combination with the blade having a right angle back flange shorter than the blade, and having the back-edge of its heel-end rounded off, of a supporting plate, one end of said plate having a tang for connection with a snath, the other end of said plate having a recess engaging one side of the blade, one margin of said recess curved to conform to the rounded heel-end portion of the blade and

one edge of said plate having a right-angle flange alining with and abutting the flange 40 of the blade.

2. A scythe blade having a longitudinal up-turned back flange, said flange being shorter than the back edge of the blade, and the heel-end of the blade cut away beyond 45 the end of said flange and also rounded-off, in combination with a supporting plate substantially triangular in plan adapted to over-lie the heel-end of the blade and having at its back edge a flange alining with 50 and abutting the flange of the blade, the under side of said plate provided with a socket having a curved shoulder to receive and support the rounded portion of the blade, said plate having a tang for connection 55 with a snath, and means for permanently securing the plate to the blade.

3. In a scythe, the combination with the blade having a right-angle back flange, said flange shorter than the blade at the heel-end 60 thereof, the back corner of the heel-end of the blade rounded-off, and its back-edge cut away beyond the end of the said flange, a supporting plate over-lying the top-face of 65 the blade and having a recess in its underside to receive the rounded portion of the blade, said plate having at its rear-edge a flange which alines with and abuts the flange of the plate, the free end of said plate having a tang, and a series of rivets 70 piercing the heel-end of the blade and also said plate for rigidly securing said parts together.

In testimony whereof I affix my signature.

SAMUEL M. KITCHEN.
